UNITED STATES PATENT OFFICE.

GEORGE F. LAUGHLIN, OF CHICAGO, ILLINOIS.

BRINE-RETAINING VALVE.

1,308,086.

Specification of Letters Patent. Patented July 1, 1919.

Application filed September 13, 1916. Serial No. 119,943.

To all whom it may concern:

Be it known that I, GEORGE F. LAUGHLIN, a citizen of the United States, residing at Chicago, in the county of Cook and State of Illinois, have invented certain new and useful Improvements in Brine-Retaining Valves, of which the following is a description.

My invention belongs to that general class of devices known as valves, and although not limited in its application to use on brine tanks, it is particularly desirable thereon, and is therefore herein illustrated and described as applied on the brine tanks of refrigerator cars. The present device is in the nature of an improvement over the siphoning device shown in my Patent No. 1,127,460, dated February 9, 1915, in which patent is set forth in full the requirements and results desired of controlling mechanism employed for this purpose. It is also fully set forth in said patent the method of icing the refrigerator cars, a substantial portion of which description is applicable to the present device, and hence need not be described in full. The present invention has among its objects the production of a device of the kind described that is simple, convenient, efficient, durable and satisfactory for use wherever found applicable. It has also as objects the production of a device that may be inexpensively manufactured and installed and will not readily get out of order. It has among its further objects the production of a device in which the ice is sure to discharge the excess brine, and thereafter close the valve, the preferred embodiment of the invention being such that the valve will automatically open and the brine be discharged upon the removing of the trap door or plug at the top of the car for icing, the valve opening at that time and closing upon the replacing of said trap door or plug.

Many other objects and advantages of the construction herein shown and described will be obvious to those skilled in the art from the disclosure herein made.

To this end my invention consists in the novel construction, arrangement and combination of parts herein shown and described, and more particularly pointed out in the claims.

In the drawings, wherein like reference characters indicate like or corresponding parts,

Figure 1 is a sectional view through a portion of the car, taken substantially on line 1, 1 of Fig. 2;

Fig. 2 is a sectional view taken substantially on line 2, 2 of Fig. 1;

Fig. 3 is a view similar to Fig. 2 of a modified construction, and

Fig. 4 is a side elevation of the same illustrating two tanks equipped with the modified construction, a portion of the tanks broken away.

Referring to the drawings, 1 and 2 represent portions of the car structure, and 3 a removable trap door or plug, arranged over the brine tanks 4. The car may be equipped with any number of tanks of suitable material, size and shape, arranged as desired, the trap door or hatch plug 3 being removable for the purpose of icing the tanks. Ordinarily a collecting pan 5 is arranged below the brine tanks, and which is provided with a drain pipe 6, and a water trap not shown in detail. I have shown an arrangement of tanks similar to that shown in my patent referred to, the tanks being spaced from each other, my preferred form of valves being provided in the walls of the adjacent sides of each two tanks with a controlling mechanism arranged between the tanks.

Referring particularly to Fig. 1, the two tanks shown are provided with discharge outlets or ports 7, arranged the desired distance above the bottom of the tanks. The passage of brine through the outlets 7, however, is normally controlled and prevented, except at such times as may be desired, by the valves 8, which are preferably arranged within the tanks. As shown, each valve 8 is provided with a packing 9, and is carried by an arm 10 pivotally secured at 11 and supported on a bracket at the exterior of the tanks. The arm 10 is formed with an extension 12 constituting substantially a bell crank therewith. The arm 10 may be secured to the valve in any suitable manner. As shown, a bracket 13 is secured to the outer side of the valve and the same pivotally secured at 14 to the arm 10.

Extending between the tanks is a control-

ling rod or bar 15, to which the arms 12 are suitably secured. I have shown connecting links 16 for pivotally connecting the arms 12 to the rod 15. If desired, a weight 17 may 5 also be arranged on the rod, the purpose of the same being more fully described hereafter.

Arranged preferably at the upper end of the rod 15 and carried by the part 2 of the 10 car structure is a lever 18, which is pivotally supported at 19 intermediate its ends by a bracket 20, or the equivalent, carried by the structure. The same is also provided with any suitable weight 21 at one end. As 15 shown, one end of the lever 18 is arranged to coöperate with the rod 15 and engage a head 22 at the end thereof. Also arranged to coöperate with the end lever 18 is a rod 23, which extends through the structure 2, 20 and is preferably formed with a head 24, the rod 23 being so disposed as to coöperate with the trap door or plug 3, as hereinafter described. The several parts may be positively connected or secured together in any 25 suitable manner.

The operation of the device may be briefly described as follows: Normally the liquid occupying the brine tanks is above the ports 7, any escape of the same being prevented 30 by the valves 8. When it is desired to re-ice the tanks, as for example at an icing station, and at which place at that time it is always desirable to empty the brine tanks, the plugs or trap doors 3 are removed preparatory to 35 icing the several tanks. As soon as the trap door 3 is removed, however, (see Fig. 2), rod 23 is released and weight 21 raises the other end of lever 18, thereby raising rod 15. As the rod is raised, however, it raises 40 the ends 12 of the bell crank 10—12, thereby opening the valves 8. The brine in the tanks flows out in the space between the tanks and down into the collecting chamber 5, and out through the drain pipe 6, until the same 45 reaches the level of the ports. As ice is placed in the tanks more brine may, of course flow out, but, of course, a portion of the same remains around the particles of ice. When the tank has been iced to 50 the desired extent the trap door 3 is replaced, and the same bears against the head 24 of rod 23, depressing the end of lever 18, and the weight of the rod and bell cranks, together with weight 17, if the same 55 is employed, causes the valves 8 to be closed, thereby preventing the escape of any further brine. Ordinarily salt or the like is placed on the top of the ice before the door 3 is positioned, and it will be noted that, the 60 brine working on the ice at the bottom, the salt at the top forming new brine, a most effective freezing mixture is obtained.

The construction shown in Figs. 3 and 4 in somewhat similar, and while not auto-

matic in operation, upon the removing or 65 positioning of the trap door, the trap door cannot be positioned without first closing the valves.

Referring to these figures, 28 represents the brine tanks, 27 a portion of the car 70 structure corresponding with part 2 of Figs. 1 and 2. In this case the ports 29 are arranged to be controlled by valves 30, which are carried by the arms 31 pivotally secured at 32, to a suitable support. The 75 valves are also each provided with a bracket 33, which is pivotally secured to a link 34 secured to rod 35. The upper end 36 of the rod 35 extends through the structure part 27 and is connected with a lever 37 formed 80 with a cam face 38 at one end and with a handle 39 at the other end.

As shown, a pin 40 carried by the lever 37 extends through a slot in the end of the rod 35, pivotally securing the parts together. 85 If desired a weight 36' may be secured on rod 35, as shown.

The operation of this form of the device may be briefly described as follows: When the lever 37 is in the position shown in 90 Figs. 3 and 4, the rod maintains the valves shut, and the lever being down, the closure may be positioned in the car roof. When the closure is removed, and it is desired to remove the brine, the handle 39 is grasped, 95 the cam working on the structure raises the rod, and thus through the links 34, simultaneously opens the valves and permits the escape of the brine. The valves may be shut when desired, but it is impossible to set the closure on the car roof closing the top of the tanks after the same have been iced, without moving the handle down, as shown in Fig. 3. It is therefore impossible to drain the tanks, and then after icing the 100 same seat the closure with the valves left open. While with this construction the valves do not open or shut with the removal or replacing of the closure, nevertheless it is impossible to seat the closure without closing the valves, and the valves are maintained closed when the closure is seated in operative position.

It will be noted that the two constructions are exceedingly simple, and the car 110 may be constructed so that they are readily accessible from the interior of the car. I have not considered it necessary to illustrate the valve seat on the tanks in detail, as this may be modified and be made to suit the 115 preference of the car builder or user. I have shown the same as applicable for controlling two valves. Obviously they will operate the same if controlling one or more than two.

Having thus described my invention, it is 12 obvious that various immaterial modifications may be made in the same without departing from the spirit of my invention;

hence I do not wish to be understood as limiting myself to the exact form, construction, arrangement or combination of parts herein shown and described, or uses mentioned.

What I claim as new and desire to secure by Letters Patent is:—

1. In a device of the kind described and in combination, a plurality of tanks, each 10 provided with a discharge port, a valve for each port arranged to normally close the same, an operating rod, means for operatively connecting said rod and valves, and means for controlling the movement of said 15 rod, comprising a lever arranged to coöperate with said rod and move the same lengthwise, and means for positively operating said lever or preventing the operation thereof.
2. In a refrigerator car of the kind described and in combination, a plurality of tanks arranged adjacent each other, said tanks provided with discharge ports in the side walls thereof, a valve for each of said 20 ports, said valves arranged on the inside of the tanks, means for pivotally securing said valves to the exterior of the tank, comprising a bell-crank lever having one end pivotally secured to said valve, a vertically 25 movable rod arranged between the tanks and extending to the top thereof, one end of each of said bell cranks connected to said rod, a lever pivotally supported intermediate its ends by the car's structure, one end of 30 said lever engaging said rod, a weight arranged at the other end of said lever, a controlling rod for said lever having one end 35 arranged to engage with said first mentioned end of the lever.
3. In a refrigerator of the kind described and in combination, a tank provided with a discharge outlet in one of the walls thereof above the bottom of the tank, a valve disposed within the tank and arranged to control said outlet, means for pivotally supporting said valve, and means for controlling the operation thereof, comprising a rod, 40 means for operatively connecting the rod and valve, and means for actuating said rod.
4. In a refrigerator of the kind described and in combination, a brine tank having an outlet in one of the walls thereof, a closure for said tank, a valve disposed within the tank and operatively supported on the exterior thereof, said valve arranged to control the discharge of the brine through said 45
5. In a refrigerator car of the kind described and in combination, a pair of brine tanks arranged with their adjacent sides in proximity to each other with a space therebetween, a closure for said tanks carried by the car structure, said tanks having discharge ports in their adjacent sides, valves for controlling said discharge ports, gravity operated actuating means for said valves including a rod operatively connected therewith, controlling means for the rod arranged to engage said closure, whereby the valves are maintained closed when the closure is in operative position.
6. In a refrigerator car of the kind described and in combination, a brine tank, a closure therefor suitably carried thereabove, said tank having a discharge port in one of the walls thereof, a valve for closing said port when the tank closure is in operative position, controlling means for said valve arranged to coöperate with said closure, whereby the closure cannot be seated with the valve open, and means for simultaneously actuating said controlling means when the closure is removed.
7. In a device of the kind described, a discharge opening for the brine, and a valve for the discharge opening, in combination with a longitudinally movable rod in proximity to the valve, a lever pivotally supported between its ends, with one end loosely engaging the end of the rod and the other end weighted to move the rod longitudinally when the lever is released, means extending to the exterior of the device for operating the lever, and operating means extending from the valve to the free end of the rod.

In testimony whereof, I have hereunto signed my name in the presence of two subscribing witnesses.

GEORGE F. LAUGHLIN.
